UNITED STATES PATENT OFFICE

WILLIAM F. BAZNER, OF CHICAGO, ILLINOIS

DESIGN FOR A PIANO CASE

Application filed January 2, 1931. Serial No. 38,190. Term of patent 14 years.

To all whom it may concern:

Be it known that I, WILLIAM F. BAZNER, a citizen of the United States, residing at Chicago, in the county of Cook and State of Illinois, have invented a new, original, and ornamental Design for Piano Case, of which the following is a specification, reference being had to the accompanying drawing, forming a part thereof.

In the drawing, Fig. 1 is a plan view, and Fig. 2 is a front elevational view of a piano case, showing my new design.

I claim:

The ornamental design for a piano case, as shown.

WILLIAM F. BAZNER.
